TYPEWRITING MACHINE

William A. Gabrielson, Syracuse, N. Y., assignor
to L. C. Smith & Corona Typewriters, Inc.,
Syracuse, N. Y., a corporation of New York

Application July 10, 1940, Serial No. 344,767

7 Claims. (Cl. 197—138)

The invention relates to improvements in typewriting machines and more particularly to paper feed ball mechanism associated with the roller platen of such a machine to hold the work sheet or sheets to the platen above the printing line.

The invention provides an improved form of paper holding and feeding ball and an improved mounting therefor upon the platen carriage of the machine, and also provides a paper ball device of the "overhead" ball type which is highly efficient in operation and may be conveniently manipulated in using the machine. The construction is also such that it may be produced at low cost and the ball may be readily and quickly attached to and disassembled from the platen carriage.

To the foregoing and other ends which will hereinafter appear from the following description of the preferred embodiment of the invention illustrated in the accompanying drawing, the invention consists in the features of construction, arrangement of parts, and combinations of parts and devices particularly pointed out in the appended claims.

In the drawing:

Fig. 1 is a fragmentary top plan view of the improved machine with the ball in its "on" or normal working position;

Fig. 2 is a fragmentary vertical longitudinal sectional view of the machine on the line 2—2 of Fig. 1;

Fig. 3 is a detail sectional view on an enlarged scale and taken on the line 3—3 of Fig. 1;

Fig. 4 is a detail sectional view similar to Fig. 3, but showing the ball in fully cast-off position;

Fig. 5 is a detail sectional view on an enlarged scale and taken on the line 5—5 of Fig. 3;

Fig. 6 is a detail view similar to Fig. 3 illustrating a method of detaching the ball from its mounting on the carriage; and

Fig. 7 is a detail perspective view showing one of the two similar pivot ends of the ball, the one shown being the one at the right hand end of the carriage.

The improvements are shown embodied in a known typewriting machine, the L. C. Smith typewriting machine, and only so much of the known machine as is necessary for a clear understanding of the present invention has been shown in the drawing and will be described.

The usual main frame 10 of the machine has the usual platen carriage 11 mounted thereon to travel back and forth transversely of the machine, and the usual roller platen structure is rotatively journaled in the ends of the carriage 12—13.

for travel therewith and for revolution of the platen roller to feed the paper, said structure including the usual rotative roller platen 12 and the usual finger wheels 13 for rotating the platen.

5 The usual pawl and ratchet line spacing mechanism for rotating the platen roller is also provided, the ratchet wheel of said mechanism being shown at 14. Rigidly held to the carriage adjacent opposite ends thereof by screws 15 are the two usual upwardly and rearwardly extending end brackets 16 located in rear of the roller platen structure. Each metal bracket 16 has rigidly secured thereto at its outer edge as usual a rigid metal end plate 17, said plates disposed vertically edgewise in vertical parallel planes extending fore-and-aft of the machine. The improvements will now be described.

The detachable paper ball consists of a pair of rigid fore-and-aft extending metal side arms 18, a front rigid metal cross rod 19 rigidly and permanently fixed at its ends to the front ends of the side arms, a pair of combined pivot and anchorage members 20 each formed of a single piece of metal and fixedly and permanently held to the rear ends of the respective side arms and extending inwardly therefrom transversely of the machine, and preferably also includes a pair of paper feed rolls 21 journaled on the cross rod 19 of the ball. The said ball is a rigid unitary structure which is detachable as a unit from the carriage as hereinafter described.

Each combined pivot and anchorage member 20 of the ball consists of a cylindrical metal stud or stud shaft 20 fixedly held to and extending axially of said shaft or stud inward from the adjacent inside face of the adjacent side arm of the ball a short distance from the rear end of the ball side arm, said stud or stud shaft being formed substantially midway its ends with a circumferential channel or groove 22 and being cut away or flattened at one side at the bottom of said groove to a diametrical line of the stud or stub shaft providing a flat diametrical wall or face 23 at the bottom of the groove the ends of which are joined by a semi-cylindrical bottom face or wall 24 of the groove, said flat wall or face 23 extending preferably across the member 20 as shown substantially longitudinally of the side arm of the ball.

50 The combined pivot and anchorage studs or stub shafts 20 of the ball are journaled removably in open bearing slots or notches 25 formed in the respective plates 17 above the brackets 16 and above and in rear of the roller platen structure 12—13. Each slot or notch 25

is open at its upper end and preferably extends upward and rearward as shown, being as wide as the maximum diameter of stud 20 and rounded or curved at its lower closed end to conform with the contour of the major body portion of stud 20.

The thickness of each plate 17 conforms substantially with the distance between the inner face of the adjacent bail side arm 18 and the outer edge of the groove 22 of the stud 20 engaged in notch 25 of said plate, and each said bail side arm is enlarged at its rear end opposite the attached stud as shown at 18a to about the outer face of the adjacent plate 17 in all rocked positions of the ball. Parts 18a are coactive with the plates 17 to assist in holding the ball in assembled working relation with the carriage and platen against axial movement of the ball.

To further hold the ball against axial movement and to releasably hold it pivotally engaged in the open-top bearing slots or notches 25, as well as for other purposes hereinafter explained, two stiff wire springs 26 are provided which extend upwardly and rearwardly at the inner faces of the respective plates 17. Between its ends, near its lower end, each spring is coiled about the shank of a screw 27 tapped in the adjacent plate 17. The lower arm of each spring 26 bears constantly against the front face of the adjacent bracket 16, and the upper arm of each spring 30 is resiliently held by the spring tension to extend at least partly, and preferably entirely, across the adjacent slot 25 at the inner face of the adjacent plate 17 with said upper arm engaged in groove 22 of the adjacent stud 20 of the ball. At its upper end each spring 26 is preferably bent to form an eye or closed loop 26a for engagement by a suitable hook to resiliently bend the upper portion or arm of the spring forward to permit the trunnions to be 41 passed through the slot mouths for attachment and detachment of the ball. Said springs 26 constantly hold the trunnions down to the bottoms of slots 25.

When the ball is assembled on the carriage with rolls 21 in contact with the platen roller 12, the flat faces 23 of studs 20 face upward and preferably also slightly forwardly, as shown in Figs. 2 and 3, with the springs 26 pressing resiliently down on the front ends of said flat faces 23 to yieldingly hold the rolls 21 to the platen or to paper passed about the platen. Upon a predetermined extent of upward and rearward swinging of the ball away from the platen, the springs 26 will no longer press on flat faces 23 but will press on the semi-cylindrical faces 24 of studs 20 and thereafter said springs will serve to frictionally hold the ball cast-off from the platen in various positions up to its maximum cast-off position. The maximum cast-off position of the ball is determined by engagement of the ball side arms with suitable stop means such as lugs 28 on plates 17.

Throughout most of the throw of the ball from its position of Fig. 4 to that of Figs. 1, 2 and 3 the springs bear on faces 24 and will frictionally hold the ball at any point. Throughout the remainder of the throw of the ball from its position of Fig. 4 to that of Figs. 1, 2 and 3 the springs press on the flat faces 23 and resiliently 70 force the ball toward the platen. Preferably the parts are so shaped and arranged that the springs 26 engage only the front ends of flat faces 23, as shown, when the studs 20 are seated in notches 25.

What I claim is:

1. In a typing machine having a platen carriage, a roller platen journalled on the carriage, and a paper-holding ball coactive with the platen, 5 means detachably pivotally holding the ball to the carriage for swinging of the ball toward and from the platen, said means comprising, in combination, a pair of journal members fixedly held to the respective side arms of the ball and detachable from the carriage with said ball, a pair of bearing supports on the carriage adjacent opposite ends of the carriage each formed with an open bearing slot for one of said journal members, a pair of springs anchored to the respective bearing supports, each spring and the adjacent ball side arm abutting opposite faces of the adjacent bearing support, each journal member having a circumferential channel in which the adjacent spring is releasably engaged, each spring having a free end portion normally extending across the mouth of the adjacent bearing slot and flexible to permit the journal member to be moved into and out of the slot.

2. In a typing machine having a platen carriage, a roller platen journalled on the carriage, and a paper-holding ball coactive with the platen, means detachably pivotally holding the ball to the carriage for swinging of the ball toward and from the platen, said means comprising, in combination, a pair of journal members fixedly held to the respective side arms of the ball and detachable from the carriage with said ball, a pair of bearing supports on the carriage adjacent opposite ends of the carriage each formed with an open bearing slot for one of said journal members, a pair of springs anchored to the respective bearing supports, each spring and the adjacent ball side arm abutting opposite faces of the adjacent bearing support, each journal member having a circumferential channel in which the adjacent spring is releasably engaged, each spring having a free end portion normally extending across the mouth of the adjacent bearing slot and flexible to permit the journal member to be moved into and out of the slot.

3. A typewriting machine having, in combination a roller platen, a paper-holding ball swingable to and from the platen, a platen carriage in which said platen is journalled having a pair of ball supporting members provided with bearing notches for the ball, the side arms of said ball provided with inwardly extending fixed trunnions journalled in said bearing notches, said side arms each abutting the outer face of a different one of said supporting members adjacent the bearing notch therein, and a pair of spring means each releasably engaged with a different one of said trunnions at the inner face of the adjacent supporting member to releasably hold the trunnion in its bearing notch and to assist the said supporting member in holding the ball against axial movement.

4. A typewriting machine as claimed in claim 3, wherein the carriage is provided with stops limiting movement of the ball away from the platen, each trunnion has a curved surface concentric with its axis and has a flat surface extending transversely of its axis, which surfaces are engageable by the adjacent spring means

as the bail approaches said stop means and said platen respectively, and each spring means is a wire spring having a trunnion engaging arm the free end of which is formed with an eye or loop to facilitate flexure of said arm to free the adjacent trunnion, each said trunnion having an annular shoulder between which and the adjacent supporting member said spring arm normally extends.

5. In a typing machine having a platen carriage, a roller platen journalled on the carriage, and a paper-holding bail coactive with the platen, means detachably pivotally holding the bail to the carriage for swinging of the bail toward and from the platen, said means comprising, in combination, a pair of journal members fixedly held to the respective side arms of the bail and detachable from the carriage with said bail, a pair 10 of bearing supports on the carriage adjacent opposite ends of the carriage each formed with an open bearing slot for one of said journal members, a pair of springs anchored to the respective bearing supports, each spring and the adjacent bail side arms abutting opposite faces of the adjacent bearing support, means to lock the bail and the journals to the bearing supports to hold the bail against lateral shifting when in paper-feeding position, each spring releasably engaging the adjacent journal and each spring having a free end portion normally extending across the 15 mouth of the adjacent bearing slot and flexible to permit the journal member to be moved into and out of the slot.

6. A typewriting machine having, in combination, a roller platen, a platen carriage in which said platen is journalled, a paper-holding bail co-active with the platen and having side arms provided at their rear ends with journals extending inwardly longitudinally of the carriage, each bail journal being formed with an annular 20 groove the bottom wall of said groove comprising a curved surface concentric with the axis of the journal and a flat surface connecting the ends of said curved surface, said carriage having a vertically arranged upwardly extending bearing plate at each side thereof the rear portions of the side arms of the said bail engaging the outer 25 faces of said plates, each plate being formed at its upper edge with upwardly opening bearing slots in which said inwardly extending journals are releasably engaged, spring means in pressing 30

engagement with the said journals, said spring means comprising a spring for each journal, each spring anchored to the carriage on the inner side of one of said bearing plates and having an upwardly extending arm engaging the inner face of said bearing plate and extending over the top of one of the journals and engaged in the groove thereof and pressing on the said curved and flat surfaces of the journal successively during rocking of the bail toward and from the platen, the journals being held between the springs and the closed lower ends of the bearing slots, said arms of the springs being flexible to release the journals for withdrawal through the open ends of the slots, whereby the springs will lock the journals to the bearing plates against axial movement and will prevent accidental withdrawal of the journals from the bearing slots, in all positions of the bail.

7. A typewriting machine, in combination, a roller platen, a platen carriage in which said platen is journalled, a paper-holding bail formed as a complete rigidly connected unit and comprising side arms provided at their rear ends with rigid journals extending inwardly longitudinally of the carriage and a rod connecting the front ends of said side arms and carrying feed rollers, said carriage having vertically arranged upwardly extending bearing plates at each side thereof, the rear portions of the side arms of said bail engaging one of the side faces of the said plates, each plate being formed at its upper edge with upwardly opening bearing slots in which said journals are removably engaged, spring means in pressing engagement with said journals, said spring means comprising a spring for each journal, each spring anchored to the carriage and having an upwardly projecting arm extending along one surface of a bearing plate on the opposite side thereof from the adjacent side arm and projecting over the top of one of the journals and pressing on the said journal during the rocking of the bail toward and from the platen, the journals being held between the springs and the closed lower ends of the bearing slots, said arms of the springs being flexible to release the journals for withdrawal through the open ends of the bearing slots and the removal of the paper bail as a complete unit.
